UNITED STATES PATENT OFFICE.

HENRY CAPEL LOFFT HOLDEN, OF LONDON, ENGLAND, ASSIGNOR TO THE UNITED MOTOR INDUSTRIES, LIMITED, OF LONDON, ENGLAND, A CORPORATION OF GREAT BRITAIN.

LAMP-HOLDER.

1,133,231.

Specification of Letters Patent. Patented Mar. 23, 1915.

Application filed March 26, 1914. Serial No. 827,413.

To all whom it may concern:

Be it known that I, HENRY CAPEL LOFFT HOLDEN, colonel, R. A., retired, a subject of the King of England, residing at London, England, have invented new and useful Improvements in Lamp-Holders, of which the following is a specification.

This invention relates to bayonet socket holders for incandescent electric lamps, electric couplings and the like, and consists of an improved contact device for providing the electrical connection with the contact or contacts upon the cap of the lamp bulb or the like.

15 The invention is particularly intended for the sockets or holders used for incandescent lamps such as are employed in electric lighting for automobile vehicles; these lamps, being of low voltage and comparatively high 20 power, require a heavier current (*i. e.* of greater amperage) than the lamps usually fitted in bayonet socket holders. For this reason the usual construction of sliding contact plunger, in which the current passes 25 either through the spring or between the sliding surfaces themselves has proved unsatisfactory in operation.

According to the present invention, the wire or connection conveying the electric 30 current extends as far as the actual contact-device or plunger which presses upon the lamp cap plate or the like and it is separated from the lamp only by the said contact-device, against which it is firmly pressed, 35 this plunger itself bearing evenly upon the lamp cap plate so as to insure definite and adequate contact with the latter. Preferably the contact device comprises a thimble having a screwed gland through which the 40 electrical connection passes, the gland serving to compress the extremity of the connection against the head of the thimble, and a spring advancing the thimble outward into contact with the lamp cap or the like.

45 Upon the accompanying drawings which illustrate two forms of construction of the invention, Figure 1 is an elevation of the lamp holder with a bayonet-cap lamp fitted in place. Fig. 2 is a section of the holder. 50 Fig. 3 is a detail showing one method of connecting the wire or flexible cable to the thimble of the contact device. Fig. 4 is a sectional elevation of a modified construction, showing the parts slightly separated. Fig. 5 is an enlarged view of the connection

employed in this modification. Fig. 6 is a sectional elevation of a complete electric lamp fitted with the invention.

The lamp holder illustrated by way of example in the drawings is of the one-piece type, in which the insulating base *a* is made integral with the head *a'*, being of porcelain or other suitable material. The brass or other casing or socket *b* may be forced upon the base and secured by indentations *c* engaged in corresponding recesses or grooves upon the base.

The wires *d* which convey the current pass through holes *e e* in the head, these holes being shouldered out at their inner ends *e'* as seen in Fig. 2. The larger bore is designed to receive the internally threaded thimble *f* forming the sliding portion of the contact device; it will be noted that this thimble is of larger diameter than the usual sliding contact pin, and that therefore a larger area of contact with the lamp cap may thus be obtained. The extremity of the flexible wire *d* is secured to this thimble by means of a screwed bush or gland *g* serving to compress the twisted or balled extremity *d'* of the conductor against the head of the thimble, as shown in section at the right of Fig. 2. The sliding thimble *f* is shown pressed outward to make contact with the usual segments upon the bayonet cap of the lamp, by means of a helical spring *j* coiled around the wire and abutting against a washer *k* while its other end presses against the shoulder of the hole *e e'*. At emerging 90 from the head *a'* of the socket or holder the connections may be secured by any suitable form of cord-grip, as desired; the part of the connection within the holder is left sufficiently loose to permit the required movement of the thimble *f* for making certain contact with the cap of the incandescent lamp.

Figs. 4 and 5 show a modified construction in which the twisted extremity *d'* of the lead is passed through an eye *f'* upon the inner end of the plunger. A gland or cap *g* screws over this eye and thus completes the direct connection of the electrical lead *d* to the plunger. The glands *g* serve 105 to limit the outward movement of the plungers; see Fig. 4.

Fig. 6 represents a lamp, such as the head-light of an automobile, fitted with the improved lamp-holder. The lamp-body *l*, in- 110

closing the glow lamp *m*, has a front door or cover-glass *n* and a parabolic or other reflector *o*. In the axis of the latter, the holder socket *b* is screwed into a bushing *q* and locked by a nut *b*¹. The multiple cable *r*, containing the leads *d* *d* is clamped at the other end of the bushing by means of a clip *s* adapted to be tightened by a screw *s*¹. The bushing *q* is slideable axially through the lamp for the purpose of focusing the lamp, and it may be locked in the desired position by a clamp *t* having a winged nut *t*¹.

It will be understood that the invention is not limited to the details of construction shown and described, and that the improved contact device may be applied to bayonet socket holders for other than the incandescent lamps for lighting *e. g.* for heating lamps or heating resistances and the like, and also for other purposes, for example, for extension plugs, adapters and the like.

Other suitable forms of lamp holders may be employed with this improved contact device.

Having thus described my invention what I claim as such and desire to secure by Letters Patent is:—

1. In a lamp-holder socket, the combination of an insulator, a plunger slideably mounted therein, and adapted to make contact with a lamp-cap, means mounted on and adjustable relatively to the plunger for securing the lead within the plunger, whereby the current is conducted directly to said plunger, and means for mechanically connecting said lead to the socket.

2. In a lamp-holder socket, an insulator, a plunger slideable therein, said plunger adapted to make contact with a lamp-cap, means including a member adjustable on the plunger for securing the lead within the plunger whereby the current is conducted directly to said plunger, and means for mechanically connecting said lead to the socket.

3. In a lamp-holder socket, an insulator, a plunger slideable therein, a spring tending to force said plunger outward into contact with a lamp-cap, means for fixing an electrical lead to said socket, and means including a member engageable with and adjustable relatively to the plunger for securing the lead within the plunger whereby the current is conducted directly to said plunger without passing through said spring.

4. A bayonet socket lamp holder, comprising a socket, means for securing an electrical lead to said socket, an insulator, said insulator mounted in said socket, and a contact-device slideable in said insulator, said contact-device comprising a thimble, a screwed gland adjustable on the thimble through which gland the electrical connection passes, said gland serving to compress an extremity of said electrical connection against an extremity of said thimble, and a spring advancing the thimble outward into contact with the lamp cap.

5. A buoyant-socket lamp holder, comprising a socket, mechanical means for securing said socket to an electrical lead, an insulator mounted in said socket, a plunger slideable in a longitudinal passage in said insulator, a shoulder in said passage, an abutment upon said plunger, a spring between said shoulder and said abutment, a screwed gland adjustable on the thimble and through which gland the electrical connection passes, said gland compressing an extremity of the electrical connection against the plunger and said spring advancing said plunger outward into contact with said lamp cap.

In testimony whereof I have affixed my signature in presence of two witnesses.

HENRY CAPEL LOFFT HOLDEN.
